UNITED STATES PATENT OFFICE.

WILLIAM M. BURTON, OF CHICAGO, ILLINOIS, ASSIGNOR TO STANDARD OIL COMPANY,
OF WHITING, INDIANA, A CORPORATION OF INDIANA.

PROCESS FOR PRODUCING WAX FROM OTHER HYDROCARBONS.

1,112,113.

Specification of Letters Patent. Patented Sept. 29, 1914.

Application filed January 21, 1914. Serial No. 813,567.

To all whom it may concern:

Be it known that I, WILLIAM M. BURTON, a citizen of the United States, residing at Chicago, in the county of Cook and State of Illinois, have invented a new and useful Improvement in a Process for Producing Wax from other Hydrocarbons, of which the following is a specification:

My invention is a process for producing paraffin wax from other hydrocarbons, its object being to secure this relatively valuable product from cheap raw material, and in a manner to permit other valuable products to be secured as well.

I have illustrated in the accompanying drawings in a diagrammatic way such apparatus as may be conveniently used for the purpose.

The single figure of the drawing represents the different devices employed in such diagrammatic form as to enable those skilled in the art readily to understand the process, the various steps being shown as clearly as is possible thereon.

In the practice of my process, I place in the still 1 a charge of hydrocarbon with a relatively high boiling-point, such as fuel oil, this oil being a relatively cheap material produced in the distillation of petroleum.

It is among the least valuable products of an oil refinery and up to a comparatively recent time has been useful principally for fuel purposes. It is sometimes used commercially for enriching water gas, hence, its synonymous name, gas oil. All the more valuable constituents are removed from it before my process commences. These valuable constituents include wax and viscous oils which are suitable for lubricants, and all low boiling-point fractions. The material which is used as the raw material in the present process is well known in the trade and under the name by which I have referred to it. But while this cheap fuel oil is the preferred raw material, the novel reactions involved in the present process are not confined to that material and its particular enumeration and description must be understood by way of a definite and preferred example. This charge is distilled in the still under pressure and at the high temperature required by the pressure. The pressure is preferably 4 to 5 atmospheres and

the temperature will normally range from 650° to 850° F. The vapors pass through a condenser 2, the distillate accumulating in a receiving drum 3. The uncondensable gases and light vapors pass out through an outlet 4. The pressure within the still 1 is preferably maintained at the desired point by manipulation of the outlet 4, the vapors being thus held under pressure not only in the still but while undergoing condensation. The distillate which accumulates in the receiving drum 3 is crude gasoline. The process thus far explained, in its preferred form, is that of my Patent No. 1,049,667, but the present process may utilize other processes than those therein described and claimed as far as the efficiency as a wax-making process is concerned. While, theoretically speaking, it is not necessary to follow that practice, as a measure of commercial efficiency the practice of that patent is preferable as the first step in the present process. Similarly, as a measure of commercial advantage, it is desirable to employ all other aids to commercial efficiency, such, for instance, as extensive catalyzing surfaces in the still 1. Such surfaces are fully described and explained in the application of Robert E. Humphreys, Serial No. 813,220, filed January 20, 1914, Process of distilling petroleum, and are now in practical use on a large scale. When operating under such preferred conditions, the distillation in the still 1 can be carried on until about two-thirds of the original charge has passed over, one-third remaining in the still as residuum. The residuum from still 1 is then transferred to a second still 5 and further distilled at atmospheric pressure until all the charge has passed over or has left a small residuum of coke. This coke residuum is very small, it being possible to distil practically all of the residue from the still 1 in the still 5. The distillate from the still 5 passes through a condenser 6, where it condenses and flows into a receiving drum 7. The distillate in the receiving drum 7 (or if desired, any fractional part thereof) is drawn off through a pump 8, and is passed through an oil-chilling machine 9 and into a press 10. The oil-chilling machine and press are diagrammatically illustrated, since both structures are well known in the art and any ordinary devices intended for the

purpose may be used. The oil-chilling machine is here shown as consisting of a series of pipes for the oil, each of which is jacketed, the intermediate space thus formed receiving chilled brine. The press will remove from the chilled oil a considerable quantity of paraffin wax, the amount being about two per cent. of the residuum distilled in the still 5. The oil expressed may be put through the operation again either by being returned directly to the still 1 or by being mixed with a fresh charge of fuel oil, but the paraffin remaining in the press is removed in the usual way. It will be seen, therefore, that the present process must involve a genuine synthesis, or at least a rearrangement of the hydrocarbon molecules, since the charge placed in the still 1 has its wax removed before the process commences, while the distillate in the receiving drum 7 contains a considerable percentage of paraffin wax which can be removed therefrom by the ordinary processes diagrammatically illustrated.

What I regard as new and desire to secure 25 by Letters Patent is—

1. The process of producing wax, which consists in successively practicing the following steps, (1) distilling a wax free hydrocarbon of high boiling point under pressure and at a temperature necessitated by the pressure, (2) distilling the residuum of the first distillation at a low pressure, (3) chilling the distillate of the second distillation, and (4) pressing out the wax. 30

2. The process of producing wax, which consists in distilling a wax free hydrocarbon of relatively high boiling point under a pressure of above 4 atmospheres and a temperature of above 650° F., then distilling the residuum of the first distillation at a low pressure, then chilling the distillate of the second distillation and pressing out the wax. 40

WILLIAM M. BURTON.
